UNITED STATES PATENT OFFICE.

SAMUEL H. CONWELL, OF CHICAGO, ILLINOIS, ASSIGNOR TO UNION METAL PRODUCTS COMPANY, OF CHICAGO, ILLINOIS, A CORPORATION OF DELAWARE.

DEVICE FOR OPERATING CAR COUPLERS.

Application filed January 11, 1926. Serial No. 80,576.

This particular invention relates to what is generally known in the art as a rotating type of uncoupling device for car couplers and comprises an operating rod, revolvably mounted on the car with brackets or in any other convenient manner, which rod is usually bent downwardly at the outer end to form a handle, and is bent outwardly at its inner end to form a crank projecting over the coupler, which crank is provided with a horizontally positioned eye with its axis perpendicular to the longitudinal center of the car. The standard vertical plane coupler has a knuckle pivoted to the coupler head and provided with a tail behind which the lock is placed. The lock lifter protrudes through and above the coupler head and is provided with a horizontally positioned eye. This lock lifter eye is $1\frac{1}{16}$ " in diameter and its axis is perpendicular to the longitudinal center of the car. This size and position has been determined by the American Railroad Association and is standard for the majority of couplers now in service.

My invention resides in the connection between the eye on the crank of the operating rod and the eye on the coupler lock lifter. When the handle is raised the rod is revolved and the crank is thereby raised which unlocks the coupler by raising the lock lifter.

The coupler moves backwardly and forwardly longitudinally of the car in buffing and draft and also moves sidewise in rounding curves, etc., and the connection between the coupler and the operating rod must permit such movements without the component parts becoming disengaged from each other or from either the coupler or the operating rod. It is frequently necessary to uncouple cars when they are coupled together and in contact so that it is impossible to throw the knuckle of either coupler. To meet this condition couplers are designed to assume a "lock set position" wherein the lock lifter can be raised from behind the tail of the knuckle and retained in such a position by means within the head of the coupler independent of the operating rod. This allows the operating rod to fall close to the lock lifter. To accommodate such a movement the connection between the operating rod crank and the coupler must fore-shorten, which is accomplished by making it of several parts which collapse by means of a

hinge joint or a sliding connection to each other. The operating rod, as above described, is old and in use on hundreds of thousands of cars now in existence. Such rods had a short chain connecting the crank arm to the lock lifter of the coupler which chains proved unsatisfactory and were responsible for a little more than half of the defects for uncoupling mechanisms reported by the Interstate Commerce Commission. These chains were defective because they were broken, missing, kinked and either too long or too short.

One of the objects of this invention is to provide a connection between the rod and the coupler which will eliminate the defects of the old chain and meet all service conditions required.

These short chains were broken by falling behind the coupler horn and being smashed between the coupler horn and the striking casting by impact of the cars in coupling. My device is designed so that the component parts cannot become disconnected from each other or from the operating rod or the coupler. The connection between the component parts and also their connections to the operating rod and the coupler are such that the device cannot become "kinked." Formerly when a brakeman wanted a small chain to repair one of the old connections he simply guessed as to the amount of chain required and applied it to the car, which accounts for the number of "too long" and "too short" chains reported by the commission. This is not possible with my device.

Another object of the invention is to provide a device wherein the component parts are identical and duplicates, therefore, interchangeable. Duplication, of course, also simplifies manufacture, handling, accounting, etc.

Another object is to obtain a device wherein the component parts are duplicates so that they cannot be wrongfully applied to the car or to each other.

Another object of the invention is to provide a device which can be assembled at the point of manufacture and shipped as a unit to the point of application to a car and which can be applied to the car by a very simple operation which requires no special tools or appliances.

With this arrangement it is not necessary to remove the operating rod from the car

or to take the coupler apart in order to install the device. This may be desirable because it is generally necessary to remove the brackets from the car in order to remove the operating rod and on steel cars these brackets are usually riveted to the car, while on wooden cars they are bolted to the car in such a manner that the inside ends of the bolts are usually inaccessible. It is undesirable to remove the lock block or lock block lifter from the coupler because of the difficulty in re-assembling the modern complicated coupler. Furthermore, if a connector can be connected to the rod and coupler while these parts are in their service position on the car, it would also be possible for the connector to become disconnected from the rod or coupler or both in service, because when the car is in service the coupler, rod and connector assume every possible relative position.

In the drawings:

Fig. 1 shows a car with my invention applied thereon.

Fig. 2 shows the assembled connector.

Fig. 3 shows a side view of the assembled connector.

Fig. 4 shows one of the members of the connector.

Fig. 5 shows a top view of Fig. 4.

Figs. 6 and 7 show the spring in detail.

Figs. 8 and 9 show a form wherein the members of the connector are hinged together.

Figs. 10 and 11 show a form wherein the members of the connector are hinged together to move laterally of the car.

In a railway car the operating rod 1 is usually mounted on the end sill 2 by brackets 3. The usual operating rod has a handle 4 and a crank arm 5, which arm has a horizontally disposed eye 6. The lock lifter 7 of the coupler 8 also has a horizontally disposed eye 9 and my invention resides in a connector for these two mentioned eyes.

The connector comprises two members 10-11 hinged together to permit the necessary fore-shortening to allow the operating rod handle 4 to return to normal position when the coupler is "lock set" and permit the coupler to move longitudinally of the car in service. The members may be flexibly connected by two eyes 12-13 to permit relative movement between the members in all directions.

Each member of the assembled connector has an open hook 14, the hook of the upper member being inserted through the eye 6 of the operating rod and the hook of the lower member being inserted through the eye 7 of the coupler lock lifter. Each member is provided with a spring 15 which is secured to it in such a manner as to close the hook, thereby forming an eye. This spring preferably bears upon the inside of the hook so

that the member may be snapped through the eye of the operating rod (or coupler lock lifter) whereby the member cannot become disconnected from the operating rod or coupler lock lifter under service conditions. To remove the member the spring is pressed back with the thumb or any convenient means.

Figs. 8 and 9 show a form wherein the upper and lower members (16-17) are hinged together by the pivot pin 18 provided with a ferrule 19 which prevents the rivet or other securing means from binding the two members together and also relieves the rivet of the shear stresses between the two members. The members are preferably duplicates.

Figs. 10 and 11 show a form wherein the upper and lower members (20-21) are hinged together by the pivot 22. Each member has jaws 23 which are provided with holes which register with corresponding holes in the other member to accommodate the pivot pin 22, and sufficient play or clearance is provided to permit freedom of movement in service. With this arrangement the pin is in quadruple shear and is prevented from bending, which bending would restrict the hinge action of the connector. This double butt hinge construction also retains the two members in alignment against lateral deflection at right angles to the permissible hinge movement. These members are preferably duplicates.

I claim:

1. In a railway car, the combination of a coupler having a lock lifter with an eye, an operating rod having an eye, and a connector comprising two members flexibly connected together, each member having a hook which engages one of said eyes and a spring element to close the hook, which element is secured to the member.

2. In a railway car, the combination of a coupler having a lock lifter with an eye, an operating rod having an eye, and a connector comprising two members hinged together, each member having a hook which engages one of said eyes and a spring element to close the hook, which element is secured to the member.

3. In a railway car, the combination of a coupler having a lock lifter with an eye, an operating rod having an eye, and a connector comprising two duplicate members hinged together, each member having a hook which engages one of said eyes and a spring element to close the hook, which element is secured to the member.

4. In a railway car, the combination of a coupler having a lock lifter with an eye, an operating rod having an eye, and a connector comprising two members flexibly connected together, each member having a hook which engages one of said eyes and a spring

element secured to the shank of the member with its opposite end engaging the inside of the hook.

5. In a railway car, the combination of a coupler having a lock lifter with an eye, an operating rod having an eye, and a connector comprising two duplicate members flexibly connected together, each member having a hook which engages one of said eyes and a spring element secured to the shank of the member with its opposite end engaging the inside of the hook.

10. In a railway car, the combination of a coupler having a lock lifter with an eye, an operating rod, and a member having a hook which engages said eye, and a spring element secured to the member, said member operatively connected to said operating rod.

20. 7. In a railway car, the combination of a

coupler having a lock lifter with an eye, an operating rod, and a member having a hook which engages said eye, and a spring element secured to the shank of the member with its opposite end engaging the inside of the hook, 25 said member operatively connected to said operating rod.

8. A connector for a railway car coupler and its operating rod comprising a pair of hook members connected together, each member having a spring element secured thereto to close the hook.

30. 9. A connector for a railway car coupler and its operating rod comprising a pair of hook members connected together, each member having a spring element secured to the shank of the member and its opposite end engaging the inside of the hook.

35. SAMUEL H. CONWELL.
